UNITED STATES PATENT OFFICE.

JULIUS CHEIN, OF MONTCLAIR, NEW JERSEY.

WAGON.

1,160,575.

Specification of Letters Patent. Patented Nov. 16, 1915.

Original application filed December 9, 1914, Serial No. 876,351. Divided and this application filed March 15, 1915. Serial No. 14,579.

To all whom it may concern:

Be it known that I, JULIUS CHEIN, a citizen of the United States, residing at Montclair, in the county of Essex and State of New Jersey, have invented certain new and useful Improvements in Wagons, of which the following is a specification, reference being had therein to the accompanying drawing.

10 My invention relates to improvements in wagons, and the object of my invention is to provide a simple and convenient device of the character described, this being a divisional application under my application 15 for a patent for wagons filed December 9th, 1914, Serial No. 876,351. I accomplish this object by the device illustrated in the accompanying drawings, in which—

Figure 1 is a view of the device complete 20 and Fig. 2 is a detail view of the tongue engaging device.

Similar characters refer to similar parts throughout the several views.

On the underside of a toy wagon body 1 25 I provide a fifth wheel or tongue engaging device comprising a plate having a base section 2, two bent over arms 3 and 4 and a triangular tongue section 5, having bent over marginal edge sections 6.

30 At the apex of the tongue section 5 I cut out a seat 7 to receive a tongue or the like for

drawing the wagon. The projecting ends or ears 8 and 9 of the marginal edge sections 6 are provided with apertures 10 and 11 respectively to receive a retaining pin. 35 The arms 3 and 4 are provided with apertures 12 and 13 respectively for the axle 14 carrying the wheels 15. An aperture 16 may be provided in the base section 2 to receive a king pin by which the tongue engaging device is secured to the underside of the wagon. 40

Having thus described my invention, what I claim is:

1. A wagon provided on its underside with 45 a plate having a triangular section provided with ears to engage a tongue and having integral axle strips depending from its base section substantially as shown and described.

2. In a wagon, a tongue engaging device 50 comprising an integral axle strip and tongue section, the latter having a bent over edge section with ears formed thereon to receive a tongue, substantially as shown and described. 55

In testimony whereof I hereunto affix my signature in the presence of two witnesses.

JULIUS CHEIN.
